UNITED STATES PATENT OFFICE

163,014

COMBINED TELEVISION AND RADIO- PHONOGRAPH CABINET

Samuel E. Adler, Chicago, Ill., assignor to Admiral
Corporation, Chicago, Ill., a corporation of
Delaware

Application December 22, 1950, Serial No. 13,535

Term of patent 14 years

(Cl. D56—4)

To all whom it may concern:

Be it known that I, Samuel E. Adler, a citizen of the United States, residing at Chicago, in the county of Cook, State of Illinois, have invented a new, original, and ornamental Design for a Combined Television and Radio-Phonograph Cabinet of which the following is a specification, reference being had to the accompanying drawing, forming part thereof.

Fig. 1 is a front elevational view of a combined television and radio-phonograph cabinet, showing my new design, the doors thereof being closed;

Fig. 2 is an elevational view of the right side of the cabinet;

Fig. 3 is a fragmentary view of the lower left portion of the cabinet as shown in Fig. 1 but drawn to an enlarged scale;

Fig. 4 is a fragmentary view, drawn to an enlarged scale, of the upper left portion shown in Fig. 1;

Fig. 5 is a sectional view taken on line 5—5 of Fig. 1; and

Fig. 6 is a sectional view on line 6—6 of Fig. 1. The left side of the cabinet resembles the right side and the back is plain.

I claim:

The ornamental design for a combined television and radio-phonograph cabinet, as shown and described.

SAMUEL E. ADLER.
